(57) **CLAIM**

The ornamental design for a display stand, substantially as shown and described.

DESCRIPTION

FIG. 1 is a perspective view of a display stand, showing our new design;

FIG. 2 is a bottom view thereof;

FIG. 3 is a first side view thereof;

FIG. 4 is a rear view thereof;

FIG. 5 is a top view thereof;

FIG. 6 is a second side view thereof;

FIG. 7 is a front view thereof;

FIG. 8 is an enlarged view of a portion of FIG. 2; and, FIG. 9 is an enlarged view of a portion of FIG. 5.

The evenly spaced broken lines are directed to environment and portions of the display stand that form no part of the claimed design.

1 Claim, 9 Drawing Sheets
